UNITED STATES PATENT OFFICE.

DARWIN S. WALRATH, OF INGHAM'S MILLS, ASSIGNOR OF ONE-THIRD TO
TITUS SHEARD, OF LITTLE FALLS, NEW YORK.

CAR-COUPING.

SPECIFICATION forming part of Letters Patent No. 247,973, dated October 4, 1881.

Application filed January 25, 1881. (Model.)

To all whom it may concern:

Be it known that I, DARWIN S. WALRATH, of Ingham's Mills, in the county of Herkimer and State of New York, have invented a new and useful Improvement in Car-Couplings, of which the following is a specification.

The object of my invention is the production of a practical self-acting car-coupling device and cushioned bumper combined, which is so constructed and applied to the platform of a car that it at the same time furnishes a yielding draw-head.

In the accompanying drawings, Figure 1 is a longitudinal section taken on the line $x-x$ of Fig. 2. Fig. 2 is a top view, showing the manner of securing the frame to the platform of the car. Fig. 3 is a front view. Fig. 4 is a section taken on the line $y-y$ of Fig. 2. Fig. 5 is a bottom view of the bumper-head.

Similar letters of reference indicate corresponding parts.

The frame is composed of the front upright pieces, A A, the top and bottom pieces, B' B, the extension or platform pieces C C, and the cross-piece D. The cross-piece D has a hole, d, made through it in the center, through which the shank or stem e of the draw-head E passes, and is formed with the tenons d' d'. The extension-pieces C C have slots c c cut in them, through which the tenons e' e' of the draw-head E pass. The shank e of the draw-head E carries the heavy spring F, which is placed between the cross-piece D and the draw-head, to force the said draw-head toward the front. The shank e is chambered, as shown in Fig. 1, and the stem or shank g of the intermediate bumper, G, with its comparatively light spring g', passes into and is inclosed by this chamber. The intermediate bumper, G, is mounted in grooves c' c', made in the extension-pieces C C of the frame, and moves in them, for the purposes hereinafter described.

The cross-bar H, which engages the connecting-bolt, is mounted in the slots a a of the uprights A A of the frame, and is moved downward by the spring h', surrounding the sleeve h, which latter passes up through the hole b, made in the center of the top piece, B', of the

frame. The cross-bar H is operated by the lever k and the chains k'', the lever provided with the grooved wheel k' being fulerumed in the stud k'' on the top piece, B', the chains passing over the wheel and down through the slot b' of this top piece, and being connected with loops or other fastening, i i, in the top of the cross-bar.

The bumper-head N is constructed with a flaring mouth and with a tapering opening or throat, n'', entirely open on the under side, as shown in Fig. 5, the upper side being partially covered, so as to form the table n, and it is also provided on the tops with a projection, n', for retaining it in place in the frame when the cars are uncoupled, and it may be faced with the rubber or similar material o, for deadening the sound when the cars come together.

The frame and draw-head are mounted in the short slots z z, formed in the beams Z Z of the platform of the car, as shown in Fig. 2. The connecting-link M is formed at each end 70 with the square heads m m, adapted to engage the cross-bar H, and made with the bolt-holes m' m' near each end, thus adapting the link to be used with the ordinary bolt-couplings.

When the cars are ready for coupling the 75 parts will be in the position shown in dotted lines in Fig. 1, with the cross-bar H resting on the table n, the bumper-head having been forced forward by the spring of the intermediate bumper when the cross-bar was raised for uncoupling. The cars to be coupled now being brought together, the connecting bolt or link M enters the mouth and throat of the bumper-head and forces it back against the intermediate bumper and the main bumper, the springs of 85 which absorb the concussion and relieve the car from the shock. In the meantime the cross-bar H has dropped from the table n into the position shown in full lines in front of the projection on the connecting-link, which prevents it from being withdrawn.

It is obvious, the cross-bar H being secured in the front of the frame, the rear of the frame being mounted in the grooves in the beams of the platform of the car, and the draw-head E 95 being limited in its forward movement in said

grooves, that the power for drawing the car will come against the rearward thrust of the heavy spring, and thus furnish a yielding draw for the car.

- 5 I have shown and described my improved car-coupling attached to such cars as have platforms; but it is obvious that it may be attached to freight and other cars which have no platforms, the bottom of the car being provided
10 with suitable beams and stays to secure it and permit its operation, and in such cases the lever for operating the cross-bar might be on the top or at the side of the car, where it may be conveniently operated.

15 Having thus described my invention, I claim as new and desire to secure by Letters Patent—

1. In a car-coupling, a frame and a draw-head having a spring between them, and both having a limited longitudinal movement in opposite directions in the platform of the car, in combination with means for retaining the connecting-link, substantially as described.

2. In a car-coupling, a frame and a draw-head separated by a spring, both having a limited movement in opposite directions in the platform of the car, in combination with the bumper-head, substantially as described.

3. In car-couplings, a frame and a draw-head separated by a spring, both having a limited movement in the platform of the car, in combination with the bumper-head and means for restraining the connecting-bolt, substantially as described.

4. The frame carrying the spring-actuated cross-bar H, the spring-actuated draw-head E,

and the intermediate bunter, G, in combination with the bumper-head N, substantially as set forth.

5. The frame having the extensions C C, provided with the slots c c, and the cross-piece D, having the hole d, in combination with the draw-head E, having the stem or shank e, carrying the spring F, substantially as set forth.

6. The draw-head E, having the chambered stem or shank e, in combination with the intermediate bumper, G, provided with a stem or shank, g, and the spring g', substantially as set forth.

7. The spring-actuated cross-bar H, having the stem h and spring h', in combination with the lever k and the bumper-head N, substantially as set forth.

8. The bumper-head N, formed with the flaring mouth and the tapering throat, and with the table n and projection n', substantially as shown and described.

9. The bumper-head N, in combination with the intermediate bumper and the cross-bar H, substantially as and for the purposes set forth.

10. The frame formed of the grooved upright pieces A A, the top piece, B', the slotted and grooved extensions C C, and the perforated cross-piece D, in combination with the stemmed draw-head E, stemmed intermediate buffer, G, cross-bar H, and bumper-head N, substantially as and for the purpose set forth.

DARWIN S. WALRATH.

Witnesses:

JOHN B. SADLER,
SAMUEL S. INGHAM.

It is hereby certified that Letters Patent No. 247,973, issued October 4, 1881, for an improvement in "Car Couplings," upon the application of Darwin S. Walrath, were improperly granted to said Walrath and Titus Sheard, as owners of the entire interest, whereas it appears, by the assignments on record in this Office, that at the time of the granting of said Letters Patent Peter Kilts was owner of one-third interest therein, and that the Patent should have been issued to said Peter Kilts jointly with said Darwin S. Walrath and Titus Sheard; that the proper corrections have been made in the files and papers relating to the case in the Patent Office, and are hereby made in said Letters Patent to make the title therein conform to the records of the Patent Office.

Signed, countersigned, and sealed this 25th day of October, A. D. 1881.

[SEAL.]

A. BELL,
Acting Secretary of the Interior.

Countersigned:

E. M. MARBLE,
Commissioner of Patents.
